(57) **CLAIM**

The ornamental design for a tactical knife, as shown and described.

DESCRIPTION

FIG. 1 is a left side view of a tactical knife showing my new design;

FIG. 2 is a left side view of a 2nd alternative embodiment of the tactical knife shown in FIG. 1;

FIG. 3 is a left side view of a 3rd embodiment of the tactical knife shown in FIGS. 1-2;

FIG. 4 is a left side view of a 4th embodiment of the tactical knife shown in FIGS. 1-3;

FIG. 5 is a left side view of a 5th embodiment of the tactical knife shown in FIGS. 1-4;

FIG. 6 is a right side view of the embodiment shown in FIG. 1;

FIG. 7 is a right side view of the embodiment shown in FIG. 2;

FIG. 8 is a right side view of the embodiment shown in FIG. 3;

FIG. 9 is a right side view of the embodiment shown in FIG. 4;

FIG. 10 is a right side view of the embodiment shown in FIG. 5;

FIG. 11 is a left perspective view from the handle end of the embodiment shown in FIG. 1;

FIG. 12 is a right perspective view from the handle end of the embodiment shown in FIG. 1;

FIG. 13 is a left perspective view from the knife end of the embodiment shown in FIG. 1;

FIG. 14 is a right perspective view from the knife end of the embodiment shown in FIG. 1;

FIG. 15 is a bottom perspective view from the knife end of the embodiment shown in FIG. 1;

FIG. 16 is a top perspective view from the handle end of the embodiment shown in FIG. 1;
FIG. 17 is a left perspective view from the handle end of the embodiment shown in FIG. 2;
FIG. 18 is a right perspective view from the handle end of the embodiment shown in FIG. 2;
FIG. 19 is a left perspective view from the knife end of the embodiment shown in FIG. 2;
FIG. 20 is a right perspective view from the knife end of the embodiment shown in FIG. 2;
FIG. 21 is a bottom perspective view from the knife end of the embodiment shown in FIG. 2;
FIG. 22 is a top perspective view from the handle end of the embodiment shown in FIG. 2;
FIG. 23 is a left perspective view from the handle end of the embodiment shown in FIG. 3;
FIG. 24 is a right perspective view from the handle end of the embodiment shown in FIG. 3;
FIG. 25 is a left perspective view from the knife end of the embodiment shown in FIG. 3;
FIG. 26 is a right perspective view from the knife end of the embodiment shown in FIG. 3;
FIG. 27 is a bottom perspective view from the knife end of the embodiment shown in FIG. 3;
FIG. 28 is a top perspective view from the handle end to the embodiment shown in FIG. 3;

FIG. 29 is a left perspective view from the handle end of the embodiment shown in FIG. 4;
FIG. 30 is a right perspective view from the handle end of the embodiment shown in FIG. 4;
FIG. 31 is a left perspective view from the knife end of the embodiment shown in FIG. 4;
FIG. 32 is a right perspective view from the knife end of the embodiment shown in FIG. 4;
FIG. 33 is a bottom perspective view from the knife end of the embodiment shown in FIG. 4;
FIG. 34 is a top perspective view from the handle end of the embodiment shown in FIG. 4;
FIG. 35 is a left perspective view from the handle end of the embodiment shown in FIG. 5;
FIG. 36 is a right perspective view from the handle end of the embodiment shown in FIG. 5;
FIG. 37 is a left perspective view from the knife end of the embodiment shown in FIG. 5;
FIG. 38 is a right perspective view from the knife end of the embodiment shown in FIG. 5;
FIG. 39 is a bottom perspective view from the knife end of the embodiment shown in FIG. 5; and,
FIG. 40 is a top perspective view from the handle end of the embodiment shown in FIG. 5.
